The ornamental design for a candle with bubbles, as shown and described.

DESCRIPTION

FIG. 1 is a perspective view of a first embodiment of a candle with bubbles showing our new design, wherein the candle simulates the appearance of a carbonated beverage in a drinking vessel;

FIG. 2 is a side elevational view of the candle with bubbles shown in FIG. 1, the other sides being identical;

FIG. 3 is a top plan view of the candle with bubbles shown in FIG. 1;

FIG. 4 is a bottom plan view of the candle with bubbles shown in FIG. 1;

FIG. 5 is a perspective view of a further embodiment of a candle with bubbles showing our new design, wherein the candle simulates the appearance of a carbonated beverage in a drinking vessel;

FIG. 6 is a side elevational view of the candle with bubbles shown in FIG. 5, the other sides being identical;

FIG. 7 is a top plan view of the candle with bubbles shown in FIG. 5;

FIG. 8 is a bottom plan view of the candle with bubbles shown in FIG. 5;

FIG. 9 is a perspective view of a further embodiment of a candle with bubbles showing our new design, wherein the candle simulates the appearance of a carbonated beverage in a drinking vessel;

FIG. 10 is a side elevational view of the candle with bubbles shown in FIG. 9, the other sides being identical;

FIG. 11 is a top plan view of the candle with bubbles shown in FIG. 9;

FIG. 12 is a bottom plan view of the candle with bubbles shown in FIG. 9;
FIG. 13 is a perspective view of a further embodiment of a candle with bubbles showing our new design, wherein the candle simulates the appearance of a carbonated beverage in a drinking vessel;
FIG. 14 is a side elevational view of the candle with bubbles shown in FIG. 13, the other sides being identical;
FIG. 15 is a top plan view of the candle with bubbles shown in FIG. 13;
FIG. 16 is a bottom plan view of the candle within bubbles shown in FIG. 13;
FIG. 17 is a perspective view of a further embodiment of a candle with bubbles showing our new design, wherein the candle simulates the appearance of a carbonated beverage in a drinking vessel;
FIG. 18 is a side elevational view of the candle with bubbles shown in FIG. 17, the other sides being identical;
FIG. 19 is a top plan view of the candle with bubbles shown in FIG. 17;
FIG. 20 is a bottom plan view of the candle with bubbles shown in FIG. 17;
FIG. 21 is a perspective view of a further embodiment of a candle with bubbles showing our new design, wherein the candle simulates the appearance of a carbonated beverage in a drinking vessel;
FIG. 22 is a side elevational view of the candle with bubbles shown in FIG. 21, the other sides being identical;
FIG. 23 is a top plan view of the candle with bubbles shown in FIG. 21;
FIG. 24 is a bottom plan view of the candle with bubbles shown in FIG. 21;

FIG. 25 is a perspective view of a further embodiment of a candle with bubbles showing our new design, wherein the candle simulates the appearance of a carbonated beverage in a drinking vessel;
FIG. 26 is a side elevational view of the candle with bubbles shown in FIG. 25, the other side being a mirror image;
FIG. 27 is a top plan view of the candle with bubbles shown in FIG. 25;
FIG. 28 is a bottom plan view of the candle with bubbles shown in FIG. 25;
FIG. 29 is a perspective view of a further embodiment of a candle with bubbles showing our new design, wherein the candle simulates the appearance of a carbonated beverage in a drinking vessel;
FIG. 30 is a side elevational view of the candle with bubbles shown in FIG. 29, the other side being a mirror image;
FIG. 31 is a top plan view of the candle with bubbles shown in FIG. 29; and,
FIG. 32 is a bottom plan view of the candle with bubbles shown in FIG. 29.
